UNITED STATES PATENT OFFICE.

ERNEST C. HEAD, OF VAN WERT, OHIO, ASSIGNOR TO COLBURN MACHINE TOOL COMPANY, OF FRANKLIN, PENNSYLVANIA, A CORPORATION OF PENNSYLVANIA.

FEED-CHANGING MECHANISM.

1,343,132.

Specification of Letters Patent. Patented June 8, 1920.

Application filed November 10, 1917. Serial No. 201,245.

To all whom it may concern:

Be it known that I, ERNEST C. HEAD, a citizen of the United States of America, and a resident of Van Wert, Ohio, have invented 5 a new and useful Improvement in Feed-Changing Mechanism, which invention is fully set forth in the following specification.

This invention relates to speed-changing mechanism and, while capable of use in a wide variety of places, has especial utility 10 when applied to the actuation of the change-speed gears in the feed train of a machine tool.

An object of this invention is to provide 15 in a machine tool, in combination with change-speed gearing including a plurality of gear members adapted by their selective actuation to drive a shaft at a plurality of speeds, simplified mechanism for actuating 20 said gear members whereby to secure said plurality of speeds.

Another object of this invention is to provide in a machine tool, in combination with a plurality of change gears related in series 25 in the feed train thereof and comprising a plurality of shiftable gear members, a single cam element for shifting said gear members into simultaneously operative positions.

30 Other objects of the invention relate to the provision of gear-actuating mechanism of the type in question which is compact in structure, efficient in operation and easy of manipulation.

35 The invention broadly considered comprises, in combination with a driven shaft of a machine tool, change-speed gearing including change-gears operatively related in series and comprising a plurality of shiftable gear members adapted by their selective actuation to drive said shaft at different speeds, a single cam and operative connections between said cam and said gear members, whereby upon rotation of said cam 40 said gear members are selectively moved into simultaneously-operative positions. In the preferred embodiment of said invention, said gear members are separately shiftable and each of said members is provided with 45 a gear-shifting element operatively connected with said cam. Means are also preferably 50

provided for indicating the position of said gear members.

The invention is capable of receiving a variety of mechanical expressions, one of 55 which is shown on the accompanying drawings, but it is to be expressly understood that the drawings are for purposes of illustration only and are not to be construed as a definition of the limits of the invention, 60 reference being had to the appended claims for that purpose.

In said drawings:—

Figure 1 is an elevation of the main operative elements of my invention; 65

Fig. 2 is a face view of the actuating cam;

Figs. 3, 4 and 5 are details of the gear-shifting elements;

Fig. 6 is an elevation of the case or box in 70 which the speed-changing mechanism is located;

Fig. 7 is an end view of said box with a portion broken away to expose the elements contained therein; and 75

Fig. 8 is an elevation of the change-speed gearing, the elements thereof which form a part of or immediately coöperate with the present invention being indicated by surface shading denoting gear teeth, and the gear-shifting elements being shown displaced for the sake of clearness. 80

Referring in detail to said drawings, wherein the same reference characters are employed to designate corresponding parts 85 in the several figures, 1 is the driving shaft of a speed-changing gear train of any suitable construction mounted within the box or case 2. Fixed on said shaft 1, in the form shown, are two gears 3 and 4. Within said 90 box and parallel to said shaft 1 is a shaft 5 having splined thereto a plurality of gear members. One of said gear members comprises gears 6 and 7 shiftable upon shaft 5 to engage gears 3 or 4, respectively. The 95 other of said gear members comprises gears 8 and 9 shiftable upon shaft 5 to engage gears 10 or 11 respectively, said last-named gears being fixedly mounted on a shaft 12 shown as independent of but in alinement with 100 drive shaft 1. Connected to gear 10 is a second gear 13 meshing with a gear 14 car-

ried by a shaft 15. In the embodiment of the invention illustrated on the drawings, said shaft 15 is a driving shaft in the feed train of a machine tool and may have associated therewith suitable clutch mechanism 16 for driving said shaft 15 from the gear 14 in the gear train heretofore described or from a rapid traverse drive 17, such, for example, as fully disclosed in my application Serial No. 201,246, filed November 10, 1917.

It will therefore be observed that shaft 15 may be driven from shaft 1 through any one of four trains of gears, *i. e.*, gears 3, 6, 15 9, 11 (as shown in Fig. 8); gears 3, 6, 8, 10; gears 4, 7, 9, 11; and gears 4, 7, 8, 10.

In accordance with the present invention, new and improved mechanism is provided for shifting said shiftable gear members to 20 any of their respective positions whereby said shaft 15 may be selectively driven through any one of the four gear trains before enumerated. In the form shown in Fig. 1, two longitudinally slidable rods 18 and 19 are mounted in the box 2 adjacent and parallel to the front face thereof. Carried by the rod 18 is a jaw or gear-engaging element 20 designed to engage and move gear 7 and thereby shift the gear member of 25 which it forms a part. Carried by the rod 19 is a jaw or gear-engaging element 21 designed to engage and move gear 9 and thereby shift the gear member of which it forms a part. Gear-engaging element 20 is shown 30 as secured to rod 18 by pin 22 and provided with an eye 23 which receives the rod 19, whereby rod 18 and element 20 move together while rod 19 slides freely through the eye 23. Gear-engaging element 21 is shown 35 as secured to rod 19 by pin 24 and provided with an eye 25 which receives the rod 18, whereby rod 19 and element 21 move together while rod 18 slides freely through the eye 25.

40 For shifting said gear-engaging elements 20 and 21, a disk 26 is mounted for rotation within said box 2, preferably adjacent the front face thereof, and provided in its rear face with a cam groove 27. While the cam 45 thus provided by the disk 26 is shown as a groove in the face thereof, it is to be expressly understood that the invention is not restricted to a cam of that type but that, by obvious modification, said disk may be substituted by a disk provided with a cam ridge or a cam face. Said disk 26 is carried by an arbor 28 having a bearing 29 in the removable cover 30 which constitutes the front face of said box 2. Attached to the outer end of 50 arbor 28 is suitable operating means, as a crank 31, which may be provided with a plunger 32 operated by a knurled handle 33 and designed to engage holes in the index 34.

The grooved face of disk 26 is shown as

parallel to and in close proximity to the 65 longitudinally movable rods 18 and 19 and is therefore closely adjacent the gear-engaging elements 20 and 21. Gear-engaging element 20 is provided on its face adjacent said disk 26 with a roller 35 adapted to engage within 70 the cam groove 27. Thereby gear-engaging element 20 is operated directly by said cam. Pivotally mounted within the box 2, as by the bolt 36, is a bell-crank lever having two arms 37 and 38, the former of which carries 75 a roller 39 adapted to engage the aforesaid cam groove 27. Arm 38 is forked at its outer end as shown at 40 and embraces a pin 41 on a collar 42 rigidly secured to rod 19. Gear-engaging element 21 is therefore indirectly operated by said cam.

By rotation of the crank 31 to engage plunger 32 with any one of the four holes designated "1", "2", "3" and "4" on the index 34, cam disk 26 with its cam groove 85 27 is rotated to occupy any one of four positions. Rotation of this cam directly engages and shifts the gear-engaging element 20 and indirectly engages and shifts the gear-engaging element 21 to thereby shift gear members 6, 7 and 8, 9 to the corresponding one of their four positions above enumerated, whereby shaft 15 may be driven through any one of the four gear trains heretofore described.

It will therefore be seen that a gear-shifting mechanism comprising a minimum number of parts has been provided, and one that is exceedingly simple and compact in construction, and easy of manipulation.

While the invention has been described as applied to the actuation of the shiftable gear members of the feed train of a machine tool, it is to be expressly understood that the invention is not limited to such an application but has utility in other connections wherein a plurality of shiftable gear members are to be selectively actuated to secure any one of a plurality of speeds of a driven shaft. Furthermore, while the embodiment 105 of the invention illustrated on the drawings has been described with considerable particularity, it is to be expressly understood that the invention is not restricted to the precise details shown but is capable of receiving a variety of mechanical expressions some of which will readily suggest themselves to those skilled in the art, while certain elements thereof are capable of use without other elements thereof. Reference 110 is therefore to be had to the claims hereto appended for a definition of the limits of the invention.

What is claimed is:—

1. A feed-changing mechanism for machine tools comprising, in combination with a plurality of change-gears operatively related in series in the feed train thereof and

- including a plurality of gear members shiftable to engage other gears thereof, a single cam, and operative connections between said cam and said gear members for shifting the 5 same.
2. A feed-changing mechanism for machine tools comprising, in combination with a plurality of simultaneously-operative groups of operatively-related gears in the 10 feed train thereof, a portion of each group of gears being shiftable to engage other gears thereof, a single cam, and operative connections between said cam and the shiftable portion of the gears of each of said 15 groups for shifting the same.
3. A feed-changing mechanism for machine tools comprising, in combination with a plurality of change-gears operatively related in series in the feed train thereof and 20 including a plurality of gear members shiftable to engage other gears thereof, a single cam, operative connections between said cam and said gear members for shifting the same, means to rotate said cam, and means to indicate the position of said shiftable gear 25 members.
4. A feed-changing mechanism for machine tools comprising, in combination with a plurality of change-gears operatively 30 related in series in the feed train thereof and including a plurality of gear members shiftable to engage other gears thereof, a single cam, and a plurality of gear-shifting elements operated by said cam, each of said 35 gear-shifting elements being operatively connected to one of said shiftable gear members.
5. A feed-changing mechanism for machine tools comprising, in combination with a plurality of operatively-related gears in the 40 feed train thereof including a plurality of gear members shiftable to engage other gears thereof, a single cam, a plurality of gear-shifting elements operatively connected to said shiftable gear members, and means intermediate said cam and said gear-shifting elements whereby certain of said 45 elements are operated directly by said cam and other of said elements operated indirectly by said cam.
6. A feed-changing mechanism for machine tools comprising, in combination with a plurality of change-gears operatively related in series in the feed train thereof and 50 including a plurality of gear members shiftable to engage other gears thereof, a single cam, and a gear-shifting element for each of said gear members separately operated by said cam.
7. In a machine tool, change gears operatively related in series and comprising a plurality of shiftable gear members, a single cam, and operative connections between each of said gear members and said cam whereby 55 rotation of said cam selectively shifts said gear members.
8. In a machine tool, change-speed gearing comprising a plurality of shiftable gear members, a single cam, a gear-shifting element for each of said shiftable gear members, and means intermediate said cam and said elements whereby certain of said elements are operated directly by said cam and other of said elements operated indirectly by said cam. 70
9. In a machine tool, change-speed gearing comprising a plurality of simultaneously-operative groups of gears a portion of each group being shiftable, a single cam, and operative connections between said cam and the shiftable gears of each group. 75
10. In a machine tool, change gears operatively related in series and comprising a plurality of shiftable gear members, a single cam, and a plurality of gear-shifting elements separately operated by said cam, each of said gear-shifting elements being operatively connected to one of said shiftable gear members. 80
11. In a machine tool, change-speed gearing comprising a plurality of shiftable gear members, a single cam, a gear-shifting element operatively connected to one of said gear members and directly operated by said cam, a second gear-shifting element operatively connected to a second of said gear members, and a lever connection intermediate said cam and said second gear-shifting element. 85
12. In a machine tool, change-speed gearing comprising a plurality of shiftable gear members, a single cam mounted for rotation adjacent said gear members, a gear-shifting element directly engaged by said cam and operatively connected to one of said gear members, and a second gear-shifting element adjacent said cam and indirectly operated thereby, said second gear-shifting element being operatively connected to a second of said gear members. 90
13. In a machine tool, change-speed gearing comprising a plurality of shiftable gear members, a single cam, parallel rods adjacent said cam, a gear-shifting element operatively connected to each of said gear members, each of said elements being connected to one of said rods and mounted on but freely movable with respect to the other of said rods, and operative connections intermediate said gear-shifting elements and said cam. 95
14. In a machine tool, a driven shaft, change-speed gearing including a plurality of gear members adapted by their selective actuation to drive said shaft at different speeds, a single cam, and operative connections between said cam and each of said gear members whereby said gear members are se- 100
15. In a machine tool, change gears operatively related in series and comprising a plurality of shiftable gear members, a single cam, and operative connections between each of said gear members and said cam whereby 105
16. In a machine tool, a driven shaft, change-speed gearing including a plurality of gear members adapted by their selective actuation to drive said shaft at different speeds, a single cam, and operative connections between said cam and each of said gear members whereby said gear members are se- 110
17. In a machine tool, a driven shaft, change-speed gearing including a plurality of gear members adapted by their selective actuation to drive said shaft at different speeds, a single cam, and operative connections between said cam and each of said gear members whereby said gear members are se- 115
18. In a machine tool, a driven shaft, change-speed gearing including a plurality of gear members adapted by their selective actuation to drive said shaft at different speeds, a single cam, and operative connections between said cam and each of said gear members whereby said gear members are se- 120
19. In a machine tool, a driven shaft, change-speed gearing including a plurality of gear members adapted by their selective actuation to drive said shaft at different speeds, a single cam, and operative connections between said cam and each of said gear members whereby said gear members are se- 125

lectively moved to simultaneously-operative positions.

15. In a machine tool, change-speed gearing comprising a plurality of simultaneously operative gear members which have a plurality of operative positions, a single rotatable cam, and operative connections be-

tween said cam and the respective gear members whereby rotation of said cam shifts the respective gear members into their several operative positions. 10

In testimony whereof I have signed this specification.

ERNEST C. HEAD.
